UNITED STATES PATENT OFFICE.

WILLIAM TURES, OF GRANVILLE, ILLINOIS, ASSIGNOR OF ONE-HALF TO
STEPHEN B. DEXTER, OF POLO, ILLINOIS.

LAMP.

SPECIFICATION forming part of Letters Patent No. 768,642, dated August 30, 1904.

Application filed January 14, 1904. Serial No. 188,945. (No model.)

To all whom it may concern:

Be it known that I, WILLIAM TURES, a citizen of the United States, residing at Granville, in the county of Putnam and State of Illinois, have invented a certain new and useful Improvement in Lamps, of which the following is a specification.

My invention relates to lamps such as employ hydrocarbon by converting it into gas for burning.

Figure 1 is a side view of a lamp with parts broken away to show portion of my invention. Fig. 2 is a cross-section on the line 2 2 of Fig. 1.

Like parts are indicated by the same letter in all the figures.

A is the body of the lamp, the lower portion of which is to be filled with the liquid, and this may be done by removing the plug B.

This plug preferably contains a valve C and two ways D E, connected therewith. The valve C is adapted to be operated to close or open either or both of these ways. Any sort of valve suitable for this purpose can be employed. Moreover, two valves could be employed, one to control each way.

F is a tube leading from the way E and terminating in the nozzle G.

H is a pipe shown in dotted line as within and extending to the bottom of the lamp-body A. This pipe is shown in the same vertical plane as the plug B; but it is placed, preferably, in the middle of the lamp, so as not to interfere with said plug. It extends up and forms one side J of the frame and continues to a point above the burner K, where it finally terminates in the discharge-aperture L, surrounded by the cup M. This discharge-aperture is partially controlled by a needle-like projection M' on the end of the valve-rod N, which passes through the stuffing-box P and is controlled by the handle R, and is provided with a valve O, adapted to engage the seat O' in the upper end of the side J of the frame. The pipe H is preferably screw-threaded on its exterior and lined inside by a gauze-like tubular body. S is the other side frame of the lamp, opposite the tube J, but similar

thereto, and its end projects freely within the cup M.

The nozzle G consists of two pipes arranged somewhat after the fashion of a tuning-fork and each provided with a series of apertures G' G'. The nozzle-arms are preferably about the same length as the pipe H and are placed on opposite sides thereof, so that the flames issuing from their apertures will proceed upwardly and inwardly toward the pipe H.

The use and operation of my invention are as follows: The plug may be removed and the reservoir be filled approximately half-full of hydrocarbon—as, for example, gasolene. The plug may be then put in place and the air-pump applied to the way D, and thus the reservoir be charged with air to any desired pressure. The valve C is then manipulated to close the way D. When it is desired to use the lamp, the valve C is manipulated until the pipe F communicates with the chamber in the lamp-body A. The vapor-charged air in the upper part of the reservoir will now pass up the pipe F and into the two arms of the nozzle G. A match applied to these arms will light the gas, and there will be a row of flames on each side of and some below but projected upwardly and inwardly toward the pipe H. Since the pipe H is open at its discharge-aperture L and closed at its other end, it will be filled with air, which is quickly heated to high temperature. If now the handle R be manipulated, the valve may be slightly unseated, and a small quantity of hydrocarbon will be forced up into the pipe H, where it begins to flow through the pipe H toward its discharge-aperture. Passing among the meshes of the gauze-like cylinder it is quickly and uniformly converted into gas and passes out in the direction indicated by the arrow into the tube S and thence into the burner of the lamp, where it is fired. The valve C may then be manipulated to cut off the starting-nozzle and the lamp will continue to work. The nozzle presents no obstruction to the action of the heat of the lamp upon the pipe H. It has no supply of air from the atmosphere, no screens or other distributing media. Its discharge-

holes are faced on opposite sides of the two branches and discharge toward each other, thus insuring a continuous combustion. The heat of the starting-nozzle is very uniformly distributed over the pipe H, and thus secures quick action in such pipe, both for preparing the same for the introduction of the liquid hydrocarbon and for the conversion of the latter into gas. The pipe in which this conversion takes place is always dry and filled with air. It gives a very uniform and perfect supply of gas without any quivering or any irregular action of the illuminating-flame. The gauze distributes the liquid, increases the heating metallic surface and assists in securing a uniform action. The pipe H is always open at one end, and there is therefore never any danger of explosion by the heating of the confined body of the liquid hydrocarbon. The exterior screw-threads on the pipe H are to quicken the heating action.

I claim—

1. In a hydrocarbon-lamp the combination of a burner, a fuel-reservoir, a screw-threaded vaporizing device with a tube of gauze ma-

terial therein and placed above the burner, and a starting-nozzle connected with the reservoir and having two branches disposed so as to act upon the vaporizing device to start the action of the same without subsequently intercepting the heat from the burner. 30

2. In a hydrocarbon-lamp the combination of a burner, a fuel-reservoir, an exteriorly-screw-threaded vaporizing-tube open to the atmosphere at its discharge end, and located 35 under the burner, a tube of gauze-like material within such vaporizing-tube, a starting-nozzle having two apertured branches, such nozzle being connected with the reservoir and so disposed as to act upon the vaporizing-tube 40 to start the action of the same without subsequently intercepting the heat from the burner, a valve for controlling the flow of fluid from the reservoir to the vaporizing-tube, and a valve partially controlling the discharge of 45 fluid from such vaporizing-tube.

WILLIAM TURES.
